[57] CLAIM

The ornamental design for a combined control panel, display unit and antenna for an emergency vehicle sensor system, as shown and described.

DESCRIPTION

FIG. 1 is a perspective view of an a combined control panel, display unit and antenna for an emergency vehicle sensor system showing my new design;

FIG. 2 is a front perspective view of the display portion thereof;

FIG. 3 is a rear view thereof;

FIG. 4 is a right side view thereof;

FIG. 5 is a left view thereof;

FIG. 6 is a top view thereof; and

FIG. 7 is a bottom view thereof;

FIG. 8 is a perspective view of the control portion thereof;

FIG. 9 is a top view thereof;

FIG. 10 is a bottom view thereof;

FIG. 11 is a front view thereof;

FIG. 12 is a rear view thereof;

FIG. 13 is a left end view thereof;

FIG. 14 is a right end view thereof;

FIG. 15 is a perspective view of the antenna portion thereof;

FIG. 16 is a front view thereof;

FIG. 17 is a bottom view thereof; and,

FIG. 18 is a top view thereof.
